UNITED STATES PATENT OFFICE.

SAMUEL E. DIESCHER, OF PITTSBURGH, PENNSYLVANIA.

MEANS FOR REGULATING WATER CIRCULATION IN WATER-TUBE BOILERS.

Application filed February 6, 1920. Serial No. 356,758.

To all whom it may concern:

Be it known that I, SAMUEL E. DIESCHER, a citizen of the United States, and a resident of Pittsburgh, in the county of Allegheny and State of Pennsylvania, made a new and useful Invention in Means for Regulating Water Circulation in Water-Tube Boilers, of which the following is a specification.

10 This invention relates to means for regulating the circulation of water through the tubes of a water tube boiler.

An object of the invention is to produce means for regulating the flow of water 15 through individual tubes of the boiler, which is capable of being easily fitted to and easily removed from the tube.

A further object is to produce means for regulating or modifying the circulation of 20 water through individual tubes of the boiler, which is so arranged and so constructed that it forms in effect a director or separator for separating the steam and the water issuing from such tubes of the boiler as enter the 25 steam liberating space of the boiler at an angle and for directing the water and steam in separate paths of flow.

These and other objects which will be 30 made apparent throughout the further description of the invention are attained by means of apparatus embodying the features herein described and illustrated.

In the drawings accompanying and forming 35 a part of this application, Figure 1 is a side elevation of a flow restricting device or plug embodying my invention and shown in connection with a fragmental sectional view of the tube sheet through which the water tube projects.

40 Figure 2 is a sectional view along the line 2—2 of Figure 1.

Figure 3 is an end view of the flow restricting device or plug shown in Figures 1 and 2.

45 The circulation of water through each individual tube of a water tube boiler is dependent somewhat upon the inclination and location of the tube in the boiler. For example, those tubes which are subjected to the 50 most heat and those which stand most nearly vertical, are subjected to a rapid circulation of the water. An unduly rapid circulation through certain of the tubes of a water tube boiler is objectionable since it occasions priming in the steam drum and as a result

the boiler delivers wet instead of steam free of moisture.

Boilers ordinarily give the best performance, from the stand point of quality of steam delivered, while operating between 60 certain definite limits above normal rating. When the boiler is operating outside of said limits it is apt to deliver steam of objectionable quality, since while the circulation throughout the entire boiler may be accelerated 65 it carries a greater percentage of water in relation to the steam and consequently the flow through certain tubes of the boiler is apt to be objectionably high in the quantity of water carried with the steam. 70 This difficulty may be obviated by employing a flow restricting device in connection with such tubes of the boiler as are subjected to an undue acceleration of the water and steam traversing them. My present invention 75 consists in the production of a flow restricting device which may be readily and easily associated with a tube of the boiler for the purpose of checking the flow through the tube.

In Figure 1 of the drawing, I have somewhat diagrammatically illustrated a water tube 4 projecting through a tube sheet 5 and flared at the end as is customary in connecting the tube to the shell of the header. The tube is shown equipped with a flow restricting device or plug 6, which is not only capable of checking the flow through it but is so equipped that it to some extent functions as a separator in that it directs the steam issuing from the tube upwardly along the tube sheet and directs the water downwardly. In this connection it may be said that vertical water tube boilers generally have the tubes so arranged that the greatest quantity of steam is generated in such tubes of the boiler as enter the steam liberating space of the top drum at an inclination, in some cases so great as to be almost horizontal, and that where I have referred to the separator action of the plug 6 I refer to its action when associated with such tubes.

As illustrated, the plug 6 consists of a head portion or cap 7 and a shank or body portion 8. The body portion is so tapered 105 that the device may be fitted to the tube by merely driving it into the opened and flared end. In addition the taper is such that the device may be readily removed from the tube when removal is necessary. As shown 110

the shank is provided with three radiating fins 9, which extend longitudinally and are so located with relation to each other that each extends in a radial direction at an angle of substantially 120° to each of the other fins. Each fin is shown as decreasing in width and radial thickness from the head towards the opposite end of the shank. With this arrangement the shank is in effect 10 tapered from the head towards the other end and may therefore be easily inserted into the end of the tube and when so inserted divides the delivery end of the tube into three separate passages of substantially equal cross sectional area. The dimensions of the plug 6 are such that when the shank is driven to place in the end of a tube, the head 7 stands away from the end of the tube a sufficient amount to provide a delivery space of adequate area for the three spaces formed by its insertion in the tube. The shank may be so formed that each fin will provide a fluid or liquid directing surface which will change the direction of the flow of the fluid or liquid issuing from the tube with a minimum amount of friction and shock. This may be accomplished by employing liberal fillets at the junction of the fins with the head. 25 The head portion is shown provided with an outer convex face so that the plug may be driven home with a hammer with little danger of breaking the head off the shank or of fracturing the head.

30 In inserting the plug into a tube, it is desirable to so locate the fins with reference to the tube that one fin points downwardly since this will provide two water delivery spaces 10 on the lower side of the tube and one steam delivery space 11 on the upper side of the tube. With such an arrangement, the natural tendency of the steam to rise is accentuated and the steam is directed upwardly as previously described. The cap 45 7 standing away from the end of the tube as shown in Figure 1 renders it easy to remove the plug when the tube with which it is associated needs cleaning, since the head may be employed in the operation of freeing the plug from the tube.

50 In the drawings I have shown the plug 6 equipped with means for holding it in place within the tube, so as to prevent it from being blown out in case it becomes loosened by vibrations of the boiler or for other reasons. As shown the plug is provided with a snap ring 13 which encircles the radiating fins and is located at a point substantially midway the length of the shank. As shown a slot 14 is provided in the face of each fin 9 for the reception of the snap ring. The ring is of such dimensions that it will engage the slots 14 and at the same time be

held into gripping engagement with the inner face of the tube when the plug is in place in a tube. In mounting the ring on the plug, the ring is placed over the small end of the shank and forced along the tapered fins until it snaps into the slots. The outer face of the ring is shown rounded. This facilitates the operation of inserting the ring and shank into the tube since the rounded face causes the ring to ride over such shoulders as may be formed on the inner surface of the tube during the operation of securing it to the tube sheet. The flare at the end of the tube accommodates the entrance of the ring. By employing such rings there is no danger of the plugs jarring loose, nor of the plugs being blown out of the tubes.

It will be apparent that the dimensions of the plug may be varied for the purpose of restricting the flow through the tubes the desired amount, that the plugs may be made of cast iron or any suitable metal.

While I have described but one embodiment of my invention, it will be apparent that various changes, modifications, additions, or omissions may be made in the plug illustrated without departing from the spirit and scope of my invention as set forth by the appended claims.

What I claim is:

1. A flow restricting plug for boiler tubes having three substantially equally spaced and radially extending tube engaging fins, each having a slot therein and a snap ring located in said slots and adapted to engage the inner face of the tube when the plug is in place in a tube.

2. A flow restricting plug adapted to be inserted into a water tube of a boiler, comprising a driving head and an integrally formed shank having a ring-engaging slot formed therein, and a snap ring surrounding said shank and engaging said slot and the inner face of the tube when the plug is in place in a tube.

3. In combination with the delivery end of a water tube of a boiler, a flow-restricting plug projecting into the flared end of the tube, comprising a shank having substantially radially-extending fins, each having a slot formed therein, and a head integrally formed with said shank and standing away from the end of the tube so as to provide a water delivery space between the tube and the head, and a snap ring located in said slot and adapted to engage the inner face of the tube when the tube is in place in the slot.

In testimony whereof, I have hereunto subscribed my name this 3rd day of February, 1920.

SAMUEL E. DIESCHER.
